UNITED STATES PATENT OFFICE

PAUL RICHARD KAEMPFER, OF DRESDEN, GERMANY

SAFETY RAZOR

Application filed September 12, 1928, Serial No. 305,545, and in Germany June 30, 1928.

The invention relates to a safety razor of known type. The novelty of the present invention resides in the special construction of the guard plate and in the combined apparatus when assembled.

5 In the accompanying drawings:

Fig. 1 is an elevation of the apparatus when closed,

Fig. 2 is a plan and

10 Fig. 3 an end view;

Fig. 4 shows the apparatus ready for use;

Figs. 5 and 7 show details, and

Fig. 6 is a section corresponding to Fig. 5.

Hitherto the guard plate for the razor blade has been of comb-like form towards the cutting edge. Owing to the prongs of the fork the skin was never completely safe from damage. According to the present invention the guard plate 1 for the blade 2 is completely closed and there are no edges so that 15 damaging of the skin is avoided. Apertures 3 are suitably located in the guard plate 1 for the escape of the lather and hair shaved off. Moreover the guard plate is not flat, but is provided with a deep recess 4 on the 20 under side.

The handle 5 of the razor is protected by a sleeve 6 which at the same time serves as an extension of said handle. In assembling 25 the apparatus it is screwed together by a screw 7. This carries furthermore a sleeve 8 in which the handle 5 together with its sleeve 6 can be inserted. The sleeve 8 is corrugated to enable it to grip the handle portion securely.

In order to enable the handle 3 to be readily unscrewed even when tightly held upon its sleeve 6, a slot 9 is provided at the place where it screws into the sleeve so that 30 it can be engaged by a flat article inserted therein.

I claim:

45 A safety razor comprising a guard plate and a backing to grip a blade therebetween, a screw to hold said parts assembled and hav-

ing a sleeve, and a handle, a sleeve in which the handle is mounted, the sleeve of the handle being insertable in and gripped by the sleeve of the screw.

In testimony whereof I have hereunto set 50 my hand this 29th day of June, A. D. 1928.

PAUL RICHARD KAEMPFER.
